Primary Examiner — Susan Moon Lee

(57) **CLAIM**

The ornamental design for a sudoku machine, as shown and described.

DESCRIPTION

FIG. 1 is a front, top perspective view of a sudoku machine, showing my new design in a fully assembled configuration; FIG. 2 is a rear, bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a front, top perspective view of the main body of the sudoku machine, shown separated for ease of illustration; FIG. 10 is a rear, bottom perspective view thereof; FIG. 11 is a front elevation view thereof; FIG. 12 is a rear elevation view thereof; FIG. 13 is a left side elevation view thereof; FIG. 14 is a right side elevation view thereof; FIG. 15 is a top plan view thereof; FIG. 16 is a bottom plan view thereof; FIG. 17 is a front, top perspective view of a key of the sudoku machine; shown separated for ease of illustration; FIG. 18 is a rear, bottom perspective view thereof; FIG. 19 is a front elevation view thereof; FIG. 20 is a rear elevation view thereof; FIG. 21 is a left side elevation view thereof; FIG. 22 is a right side elevation view thereof; FIG. 23 is a top plan view thereof; and, FIG. 24 is a bottom plan view thereof.

The broken lines in the figures illustrate portions of the sudoku machine that form no part of the claimed design.

1 Claim, 24 Drawing Sheets
